UNITED STATES PATENT OFFICE.

EDWARD E. CLEMENT, OF WASHINGTON, DISTRICT OF COLUMBIA, ASSIGNOR, BY
MESNE ASSIGNMENTS, TO THE NORTH ELECTRIC MANUFACTURING COMPANY.

TELEPHONE-EXCHANGE SYSTEM.

Application filed April 15, 1905. Serial No. 255,830.

My invention relates to telephone exchange systems, and has for its object the production of such a system which shall be highly efficient and economical in operation and maintenance. I may designate my system generally as a clearing house system, that is, I provide a main central exchange with trunk lines running to branch exchanges, and at the branch exchanges I install automatic switching apparatus of a peculiar kind. The subscribers' lines radiate from the branch exchanges, and the subscribers' instruments are simple telephone sets the same as used in any manual system, without any complication whatever. I shall describe the system as full, common battery, with double supervision at central, provision for recall, and all the time and labor-saving contrivances which belong to a modern manual system. The most noticeable feature is the location of all operators at the main central exchange or clearing house, and the provision I make for the uniform distribution of the entire exchange load or rather of the loads of all the branch exchanges among all the operators. This is accomplished by bringing in the trunks from each branch exchange and instead of landing them all for answering purposes before a particular operator at one position, or one section, I distribute them uniformly among all the operators. The effect of this is that no matter what fluctuation occurs, in what branch exchange, it affects all the operators, and this is particularly so because I make provision for reversing the distribution so to speak, or arranging it in echelon, so to speak, the subscribers moreover, selecting idle trunks, so that the subscribers at each branch exchange do the distributing unconsciously. The number of automatic switches at each branch exchange is less than the number of lines. When a line calls it gets on a control circuit which applies current to and starts the first idle trunk switch to connect that switch with the calling line. According to one form of the invention, the trunks may be two way, each provided with a pair of automatic switches at the branch exchange, and according to another form they are one way, one-half of them, or whatever other proportion is required, being for incoming business, and the rest for outgoing

business, the terminal switches being built and connected accordingly.

In order that the number of trunks in a large city may be economized as much as possible, and with the knowledge that the fluctuations in load vary definitely according to the character of the subscriber's line, it is part of my invention to arrange for relief trunks. That is, I run a body of trunk lines, embracing part or all of a trunk cable, to and through one branch exchange to another one. Suppose the first exchange is in a business district, and the second is in a residence district; the peak of the load curve in the former is between eleven and twelve o'clock in the morning, with a somewhat shorter horn early in the afternoon, while the peak of the load in the residence district is after the close of business hours. By combining two branch exchanges (or for that matter, as many as economy dictates), the trunks may be used at a high percentage of efficiency during a longer period and with less loss from idleness of investment than if two sets were used. In a city like New York, a single main cable might be run from a downtown exchange up the island to a point above Harlem, or even farther, with anywhere from two to twelve exchanges, taking off multiple taps, to the main office which might be located anywhere along the main body, or at the large end of the cable. All connections will be made in this main office, and I can conceive of no greater means of economy in every respect than this combination of a centralized working force under a single management, and a reduced cable system with the numerous elements i. e., the subscribers' lines, reduced to short lengths. Approximate estimates show that a saving of at least ten per cent in operating expenses is thus effected, and an enormous saving in cable, the latter, whether or no the relief or multiple tap system is used. In using the latter, I prefer to have certain wires in the cable allotted to each branch exchange during specified hours, and shifting this allotment as the load shifts. Thus, pairs Nos. 2114 to 2210 might be allotted to a business exchange until four p. m., and thereafter be taken up by a residence exchange. I consider myself to be the originator of every feature of this and all other arrangements, cir-

cuits, methods, and apparatus, herein set forth, and I shall claim all the same broadly and specifically.

I am aware that it is objected that in 5 trunking to a central office from an automatic branch exchange the operators may not know who is calling, as they would in a plain manual system, but I consider this an advantage, as it positively does away 10 with favoritism. In my system, a subscriber calling a dozen times in succession is liable to come in on as many different positions, over as many different trunks, and in a large exchange or clearing house the operators 15 would get a very shifty and shifting chance for acquaintanceship.

My invention is illustrated in the accompanying drawings, wherein Figure 1 shows the subscriber's station terminating in the 20 multiple contacts of a trunk connector switch at a sub-exchange or station, also the sub-exchange end of the central office trunk, to which is connected the connector switch. The trunk to central office in this case is a 25 single-way trunk. Figure 2 is a similar diagram showing the central office ends of two trunks, one being used for incoming calls, while the other is used for outgoing calls. The cord-circuit is also shown, which 30 forms the connecting link between these trunks. Figure 3 shows the outgoing end of a trunk at the sub-exchange, also the subscriber's line apparatus at sub-station. Figure 4 shows the subscriber's station terminating in multiple contacts of two trunk 35 connector switches, both of these switches being connected to the trunk, one being the active switch for outgoing calls, the other being the idle switch used for incoming 40 calls. Figure 5 shows the central office end of two two-way trunks, one being used to illustrate an incoming call, the other for an outgoing call. The cord-circuit is also 45 shown, which serves as the connecting link between these two trunks. Figure 6 is a duplication of Figure 4 and is used in illustrating a two-way trunk being used for an outgoing call; Figure 4 illustrating a two-way trunk being used for an incoming call. 50 The apparatus and the wiring in several of the figures being identical, the same lettering is observed throughout. Figure 7 is a diagram illustrating the distributing scheme for a clearing-house system. Figure 55 8 is a portion of a diagram illustrating the row and individual wipers of the line finder switches.

The scheme shown in Figures 4, 5 and 6 is a combination of the incoming and outgoing trunks shown in Figures 1, 2 and 3. In the latter I have shown two trunks, one being used as an outgoing trunk and the other as an incoming trunk. In Figures 4, 5 and 6 I have combined the two switches in one trunk so that the same trunk may be

used for both incoming and outgoing calls. This change is made without altering the wiring or apparatus in the least, with the exception of adding three contact springs, z^{35} , z^{36} and z^{37} to the outgoing switch to be 70 operated by the spindle.

In describing Figures 4, 5 and 6 it will not be necessary to describe Figures 1, 2 and 3, as the operation is identical in each case.

Referring now to Figure 4, A is the subscriber's station, equipped with apparatus usual in common battery systems. It consists of a transmitter T, receiver R, hook H, ringer Q and condenser L. The line-wires 1 and 2 from this station terminate in multiple contacts z^{12} and z^{13} in the idle connector switch Z and in the multiple terminals z^{28} and z^{29} of the active connector switch Z'. The line apparatus controlling 55 these switches consists of the following: line relay M, retardation coil N, cut-off relay S. The line relay M is connected to the line wire 1 by the wire 3, the other terminal being grounded. The contact m^1 makes a 60 momentary connection with the contact m^4 when the relay M is energized. This momentary connection is made to start the idle switch Z. The contacts m^2 in all the line relays are connected by the common wire 65 10. This common wire 10 in part forms the starting circuit of the idle switches for all the lines in each exchange or group. Contact m^4 is grounded through the contacts s and s' of the relay S, and when this relay 105 is energized these contacts are broken, as is necessary for an outgoing call to prevent the switch from operating upon the relay M becoming energized when the called subscriber answers. The common wire 10 is 110 connected to the starting relay S' in the connector switch Z by the following path: wire 17, contacts z^{10} and z^{11} , wire 24, contacts z^{36} and z^{37} , wire 240, contact s^8 , winding of the relay S' to battery. One terminal of the relay S is connected to the multiple terminals z^{16} and z^{32} , the other terminal being grounded. The contact s^4 of the relay S is connected to the row contact z^{14} 115 and contact s^2 to the individual contact z^{15} . The contact s^3 is connected to the wiper z^{21} of the connector switch Z' by the wire 9 and also to the contact m^2 of the relay M by the wire 6. The retardation coil N is connected to the wire 2 by the wire 4, the 120 other terminal being connected to battery by the wire 5. The row contact z^{14} affords a means for stopping the connector switch Z on the desired row of terminals in which the calling line is located, while the individual contact z^{15} forms a means for stopping the wipers of the switch Z on the contacts of the line calling. The idle connector switch circuit Z includes the following: starting relay S' and relay S², which con- 125 130

trol the side switches X and X' , the vertical magnet F , rotary magnet F' , release magnet W , interrupting machine G , spindle z , on which are mounted the trunk wipers z' ,
6 z^2 , row wiper z^3 , individual wiper z^4 and wiper z^5 for operating the cut-off relays S and S^{10} , and the wiper z^6 which jointly controls the release magnet W . One terminal of the relay S' is connected to the common starting wire 10 by the path already described, the other terminal being connected to battery. One terminal of the relay S^2 is connected to the wipers z^3 and z^4 by the wire 21, the other terminal being connected to battery by the wire 30. The contact s^7 of the relay S' is connected to the blade of the switch X' by wire 26. One terminal of the vertical magnet F is connected to the contact s^4 of the relay S' by the wire 29, the other terminal being connected to the first point in the side switch X by the wire 27, one terminal of the rotary magnet F' is also connected to the contact s^4 by the wire 29, the other terminal being connected to the second point in the side switch X by wire 28. The contact s^6 of the relay S' is connected to the blade of the switch X by wire 31, while the contacts s^3 and s^5 are connected to the bus-wires leading to the interrupting machine G . One terminal of the release magnet W is connected to the contact spring z^8 by wire 32, the other terminal being connected to battery. The contact w^2 is connected to the relay S^2 by the wires 23 and 21, contact w' being grounded.

40 Contacts w' and w^2 , when in connection at the end of a conversation, energize the relay S^2 and restore the side switches X and X' to their normal or starting position. The active connector switch Z' can be in the form of any standard switch responding to the vertical and rotary impulses of a transmitter or sending device. In this case, 45 for illustration I have shown the switch commonly known as the Strowger, which is illustrated and described as to its mechanical features in U. S. Letters Patent to Keith and Erickson No. 815,176 dated March 13, 1906. This circuit comprises the following: vertical relay S^8 ; rotary relay S^9 ; test relay X ; ringing relay Y ; vertical magnet s^{58} ; rotary magnet s^{59} ; release magnet W' and side switches z^{24} , z^{25} , z^{26} and z^{27} . In 50 addition to the foregoing I have added a cut-off relay S^{10} for the purpose of cutting off the vertical and rotary relays and short-circuiting the condensers when the trunk is being used. I have also added the wiper z^{22} for controlling the cut-off relay S^{10} , and the wiper z^{23} for controlling the cut-off relay S of the line circuit for reasons which 55 will be shown later. I have also added springs z^{35} , z^{36} and z^{37} controlled by the spindle z^{18} . These springs are arranged in 60

series with the corresponding springs of the switch Z controlled by the spindle z for the purpose of cutting off the idle switch when it is in use and cutting on the next succeeding idle switch.

Referring now to Figure 5, the central office end of the trunk from the sub-station terminates in the springs j and j' , respectively, of the jack J. The trunking apparatus consists of the signal relay M' , one terminal of which is connected to the trunk wire 20 by the wire 35, the other terminal being grounded through the wire 36, contacts n^2 , and n' of the cut-off relay N' . The relay M' jointly controls the busy lamp n 80 and directly controls the signal lamp m^5 . One terminal of the cut-off relay N' is connected to the thimble j^2 of the jack J by the wire 39. The relay N' jointly controls the busy lamp n and disconnects the signal 85 relay M' when energized. I have thus described the central office end of the incoming trunk, and as the central office end of the outgoing trunk is identical it will need no description. The cord-circuit consists of the following: the answering plug P, calling plug P' , supervisory relay S^3 , retardation coil I, controlling relay S^4 , answering supervisory lamp s^{10} , calling supervisory relay S^{15} , retardation coil I' , 90 controlling relay S^6 , calling supervisory lamp s^{15} and the automatic trunk disconnecting relay S^7 . The tip p of the answering plug P is connected to the tip p of the calling plug P' by the following path: strand 44, condenser L, contacts k' , k^2 of key K, strand 46; sleeve p' of the answering plug P connected to the sleeve p' of the calling plug P' by the following path: strand 45, condenser L' , contacts k^4 , k^3 of key K and strand 47. Relay S^3 is connected to the strand 44 by the wire 48 and to ground by the wires 52 and 66. One terminal of the retardation coil I is connected to the strand 45 by the wire 49, the other terminal connected to ground by the wires 52 and 66. Contact s^{12} of the relay S^3 is connected to the supervisory lamp s^{15} and to the contact s^{17} of the relay S^{15} by the wire 61 and from there to battery through the contact s^{16} and the wire 60. The contact s^{11} is connected to one terminal of the relay S^7 and the contact s^{25} , the other terminal of the relay S^7 being connected to one terminal of the lamp s^{15} and contact s^{21} of the relay S^6 by the wires 57 and 63. Contact s^{24} of the relay S^7 is connected to the strand 46 by the wires 62 and 50, and the contact s^{23} is connected to the strand 47. The contact s^{22} is connected to battery by the wires 59 and 60. One terminal of the relay S^{15} is connected to the strand 46 by the wire 50, the other terminal being connected to ground by the wires 67 and 64. One terminal of the retardation coil I' is connected 100 105 110 115 120 125 130

to the strand 47 by the wire 51, the other terminal being connected to ground by the wires 67 and 64. One terminal of the relay S^6 is connected to the third conductor p^2 of the calling-plug P' by the wire 65, the other terminal and contact being grounded.

Figure 6 being identical with Figure 4 will need no description, but the operation will be explained in the proper order.

- 10 The operation of my system is as follows: Referring now to Figure 4, the subscriber taking down his receiver closes the circuit of the line relay M , which attracts its armatures and a passing ground is placed on the 15 common wire 10, which affects the starting relay S' in the idle connector switch Z by the following path: ground, contacts s , s' of the relay S , wire 8, contacts m^4 , m^3 of the relay M , common wire 10, wire 17, contacts 20 z^{10} , z^{11} of the connector switch Z , wire 24, contacts z^{26} , z^{27} of the active connector switch Z' , wire 240, relay S' to battery. The relay S' being now energized attracts its armatures and connects the interrupting machine 25 G to the vertical magnet F through the first contact in the side switch X . The vertical magnet F now operating causes the spindle z carrying the wipers, to step in a vertical direction until the wipers come to rest on the 30 row containing the multiple contacts of the calling line. The wipers come to rest in the desired row on account of the ground being placed on the row contact by the relay M when it first became energized. This ground 35 is traced by the following path: row contact z^{14} , wire 12, contacts s^2 and s^3 of the relay S , wire 9, wire 6, contacts m^2 and m of the relay M to ground. Ground is also placed on the individual contact z^{15} at the same instant and by the same relay. These contacts, 40 the spindle z , the vertical and rotary magnets F and F' and the wipers are all shown as to their mechanical arrangement in Figure 8. As shown in this figure, the row contacts are arranged in a single vertical row, in order that the proper level may be selected, and the individual contacts are arranged with a number of them, as ten, in each row or corresponding to each level. As 45 soon as the wiper z^8 comes in contact with the terminal z^{14} the relay S^2 which controls the side switches X and X' , is energized, causing the side switches to take one step. This one step cuts off vertical magnet 50 F and cuts on in its place the rotary magnet F' . Under the influence of this magnet the spindle z , carrying the wipers, begins to rotate and continues to rotate until the individual wiper z^4 comes into contact with the terminal z^{15} . The relay S^2 is then energized the second time, the side switch makes one more movement, which disconnects the rotary magnet F' and at the same time releases the relay S' by disconnecting the 55 ground from the contact s^7 , which was at that time in connection with the contact s^8 leading through the winding to battery. The wipers now resting on the contacts of the line which originated the call, the wiper z^5 , to which is connected the cut-off relay S^{10} , connects with the contact z^{16} , which energizes the cut-off relay S , which upon attracting its armatures disconnects the ground or busy signal from the row wiper z^{14} and the individual wiper z^{15} by breaking the contacts s^2 , s^3 , s^{52} and s^{53} . The contacts s and s' are also broken for use in outgoing calls which disconnect the ground from the contact m^4 of the relay M to prevent the starting circuit being closed when the called subscriber 60 answers. The wiper z^6 , which jointly controls the release magnet W , is now connected to the contact z^{17} leading to the contact m' of the relay M . The release magnet W is now placed under the control of the line relay 65 and is energized when the calling subscriber hangs up his telephone. The spindle z , in making its first vertical movement, disconnected the starting relay S' by breaking the contacts z^{10} and z^{11} . The relay S' being disconnected from the common wire 10 cannot be energized by any other line relay until at the end of the conversation, when the contacts z^{10} , z^{11} are again connected. At the first 70 movement of the spindle z the contacts z^9 and z^{10} were closed, which cut on the next idle switch to the wire 10 by the following path: wire 17, contacts z^{10} and z^8 , wire 14 to the next idle switch. The contacts z^7 and z^8 were also closed at the same time, which connected the release magnet W to the wiper z^6 . The wiper z^5 to which is connected the cut-off relay S^{10} of the active switch Z' being now connected to the contact Z^{16} leading to the winding of relay S , said relay S^{10} becomes energized, attracts its armatures, cuts off the vertical and rotary relays S^8 and S^9 , respectively, short-circuiting the condensers L^3 and L^4 . The calling subscriber is now connected to the clearing-house or central office through the trunk wires 19 and 20. This connection being completed, the signal relay M' is placed in series with the retardation coil N , Figure 4, by the following path: 75 battery B , wires 18 and 5, N , wires 4 and 2, contact z^{13} , wiper z^2 , wires 20 and 35, M' , wire 36, contacts n^2 and n' of the relay N' to ground. The relay M' thereupon becomes energized attracting its armatures, causing the signal lamp m^5 to glow by closing the contacts m^6 and m^7 . The busy lamp n is also caused to glow by closing the contacts m^3 and m^6 . This busy lamp n and the jack J are multiplied in each position. The operator upon perceiving the line signal inserts the answering plug P into the jack J , causing battery to flow to the relay S^4 and the cut-off relay N' in series by the following path: ground, S^4 , wire 56, p^2 , j^2 , wire 39, N' , wires 42 and 40 to battery. The relay N' becomes 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

the vertical and rotary relays S^8 , S^9 , respectively, and short-circuits the condensers L^2 and L^3 . The called subscriber is now connected straight through to the clearing-house over line wire 1 by the following path: side switch z^{26} , wire 74, contacts z and z' , wires 72, 83, contacts s^{33} , s^{31} of the relay S^{10} , wires 78 and 70 to j of the jack J' , Figure 5; and over No. 2 side of the line by the following path: z^{29} , z^{20} , wire 77, side switch z^{26} , wire 75, contacts z^3 , z^4 , wires 73, 84, contacts s^{24} , s^{25} , of the relay S^{10} , wires 81 and 71 to j' of the jack J' , Figure 5. Relay S^{15} , Figure 5, being in multiple with the line relay M , Figure 6, of the called subscriber's line, becomes energized when he takes down his receiver, which extinguishes the lamp s^{15} , notifying the operator at the clearing-house that the call is answered. At the end of the conversation the calling subscriber hanging up his telephone opens the line-circuit 1-2, which deenergizes the line relay M , closing the contacts m , m' . The circuit of the release magnet W is closed and upon attracting its armatures it releases the switch Z , and all parts are returned to their normal or starting position and the switch again connected to the starting circuit 10. The wiper z^6 , leaving the contact z^{16} opens the circuit of the relay S^{10} which removes the short-circuit from the condensers and again connects the vertical and rotary relays of the active connector switch Z' .

Referring now to Figure 5, relay S^8 also becomes deenergized and the circuit of the lamp s^{10} is closed, causing it to glow, notifying the operator that the calling subscriber has hung up his telephone. The contacts s^{12} , s^{11} are now closed and the relay S^7 has its circuit partly completed. The called subscriber in hanging up his telephone opens the circuit of the line relay M , Figure 6, which breaks the contacts m^2 and m^3 , releasing the cut-off relay S^{10} in the active connector switch Z'^{-2} , which removes the short-circuit from the condensers and again connects the vertical and rotary relays S^8 and S^9 . The relay S^{15} , Figure 5, also becomes deenergized when the called subscriber hangs up his telephone, and its armature falling back closes the contacts s^{16} , s^{17} , causing the lamp s^{15} to glow. At the same time the closing of the contacts s^{16} , s^{17} completes the circuit of relay S^7 . The relay S^7 becoming energized attracts its armature and connects battery to the vertical and rotary relays S^8 and S^9 , Figure 6, by the following paths: battery B, wires 60 and 59, contacts s^{22} , s^{24} , wires 62, 50, strand 46, p , j , wires 70, 78, contacts s^{31} , s^{32} of the relay S^{10} , Figure 6, wire 79, S^8 , wire 80 to ground; and from battery B, wires 60, 59, contacts s^{22} , s^{23} , wires 58, 51, strand 47, p' , j' , wires 71, 81, contacts s^{35} , s^{36} of the relay S^{10} , Figure 6, wire 82, S^9 , wire 80 to ground. Both

relays S^8 and S^9 are energized simultaneously over both sides of the trunk by battery to ground, and attracting their armatures close the contacts s^{26} and s^{30} , completing the circuit of the release magnet W' , which becoming energized restores the connector switch Z'^{-2} to its normal position, the spindle in falling closing the contacts z^{36} and z^{37} , putting its mate idle switch Z^2 back on the starting circuit 10. The relay S^7 , Figure 5, remains energized or locked through the contacts s^{20} and s^{21} of the relay S^6 by the following path: battery, wires 60 and 59, contacts s^{22} , s^{25} , winding of the relay S^7 , wires 57, 63, contacts s^{21} , s^{20} of the relay S^6 to ground. It will be seen that the battery being placed on the strand 46, relay S^{15} becomes energized, attracts its armatures, breaks the contacts s^{16} , s^{17} and would extinguish the lamp s^{15} . This contingency is provided for by the terminal of the lamp leading to the contact s^{17} , being connected to battery by another path as follows: wire 61, contacts s^{12} , s^{11} of relay S^8 , wire 53, contacts s^{25} and s^{22} of relay S^7 , wires 59 and 60 to battery. The operator upon seeing both lamps glowing withdraws the plugs from the jacks and the relays S^4 and S^6 become deenergized; relay S^4 disconnecting the lamp s^{10} , and the relay S^6 releasing the relay S^7 , which in turn extinguishes the lamp s^{15} and releases the relay S^{15} .

In the foregoing description I have shown two two-way trunks both being identical, one being used as an incoming trunk and the other as an outgoing trunk, so it follows that each trunk may be used either for an incoming or an outgoing call as the case may be. In Figures 1, 2, and 3 the trunks are shown as single trunks, that is the trunk shown in Figure 1 can only be used for incoming calls, while the trunk shown in Figure 3 can only be used for outgoing calls, and in the central office end of the outgoing trunk, Figure 2, the line relay and signal lamp are of course omitted.

Referring now to Figure 7, I have shown diagrammatically the distributing scheme as applied to the clearing-house system. A, B, C and D represent four sub or branch exchanges with trunk lines connected to the clearing-house. A', B', C' and D' represent groups of trunks from their respective stations. a' , a^2 , a^3 , etc., b' , b^2 , b^3 , etc., c' , c^2 , c^3 , etc., d' , d^2 , d^3 , etc., represent these groups of trunks being distributed to the answering jacks at the various operators' positions, 1, 2, 3, 4, 5, 6, etc. It will be noticed that the trunks from each sub-station are distributed equally among the various operators' positions at the clearing-house, so that the load at all times is practically uniform at all positions. A², B², C², and D² represent the different groups of trunks from the sub-exchanges being carried to multiple jacks in

the sections 1, 2, 3, each group being multiplied in each section so as to be in reach of any operator to be used for outgoing business. By this method of distribution no one operator will be overburdened with work, while another operator is idle, and besides no girl can tell from her line-signal the number of the line calling, that is the number of the subscriber's telephone, as his signal may come in on any trunk from the sub-exchange and to pick out a different girl at each call. Thus it will be seen that the operator can show no favoritism to the calling subscriber by giving his call preference over others.

Having thus described my invention what I claim and desire to secure by Letters Patent is:—

1. In a telephone system, a plurality of telephone lines, a plurality of trunks, Y-switches, one associated with each of said trunks and each adapted to connect its associated trunk to a calling one of said telephone lines, line controlled relays associated with said telephone lines, and a motor circuit extending from one of said Y-switches and branching in multiple to contacts of said line relays whereby, when any line is calling, said motor circuit will be closed by the line relay contact of the calling line, causing the motor mechanism of said Y-switch to operate.

2. In a telephone system, a plurality of telephone lines, a plurality of trunks; Y-switches, one associated with each of said trunks and each adapted to connect its associated trunk to a calling one of said telephone lines, line controlled relays associated with said telephone lines, a motor circuit extending from a predetermined Y-switch and branching in multiple to contacts of said line relays, whereby, when any line is calling said motor circuit will be closed by a line relay contact of the calling line causing the motor mechanism of the predetermined Y-switch to operate, and means in the operating Y-switch to extend said motor circuit to the motor mechanism of another Y-switch when the operating Y-switch connects with the calling line, substantially as described.

3. In a telephone system, a plurality of telephone lines, a plurality of trunks; Y-switches, one associated with each of said trunks and each adapted to connect its associated trunk to a calling one of said telephone lines, line controlled relays associated with said telephone lines, a motor circuit extending from one of said Y-switches and branching in multiple to contacts of said line relays, whereby, when any line is calling said motor circuit will be closed by a line relay contact of the calling line causing the motor mechanism of said Y-switch to operate, and means in each Y-switch for remov-

ing its motor mechanism from said motor circuit when the Y-switch is busy, substantially as described.

4. An exchange system comprising a central station, telephone lines extending thereto, switching mechanisms to which the lines are connected, a unitary device individual to each line at the central station for controlling any one of its switching mechanisms, and means individual to each switching mechanism for transferring the line control from it to another switching mechanism.

5. An exchange system comprising telephone lines, switching mechanisms to a plurality of which each of the lines is connected, each switching mechanism including a plurality of sets of fixed contacts and a set of movable contacts adapted in its travel to successively engage the sets of fixed contacts, starting means associated with each switching mechanism, and line controlled means individual to each line adapted to directly control the starting means of any one of the switching mechanisms to which the line is connected.

6. In a telephone exchange system, a plurality of line circuits, link circuits for interconnecting the lines, and primary selector switches for connecting calling lines with said links, each of these switches containing terminals of the lines divided into groups, testing contacts associated with the several groups, a test wiper for the group or row test contacts, means for driving a switch in response to a call over any one of the lines represented in its banks, so as to impel its test wiper over the row test contacts, means adapted to stop the switch when the test wiper rests upon the test contact associated with the group or row of individual contacts in which a contact of the calling line appears, and means thereupon becoming effective to drive the switch into connection with the individual contacts of the line calling.

7. In an exchange system, a plurality of circuits to be selected, and a testing selector switch containing testing contacts forming terminals of said circuits, arranged in successive groups or rows, and a common test contact associated with each group, test wipers and means for actuating the switch with two motions for groups and individual selection, together with means responsive to the test on the group contacts, for shifting the motion from group selection to individual contact selection.

8. In a telephone exchange system, a plurality of circuits and a two motion selector switch containing terminals thereof arranged in parallel rows, and means for actuating the co-operating switch terminals so as to test first for a group or row and then for an individual contact in the row.

9. In a telephone exchange system, a testing selector switch comprising the following instrumentalities: a contact bank containing a plurality of rows of terminals, an associated set of test terminals, comprising one test terminal for each row, a spindle carrying wipers adapted to co-operate with the individual contacts in the rows and with the associated row contacts, actuating magnets 70 for the spindle, and circuits for said magnets automatically controlled in the operation of the wipers.
10. In a telephone exchange system, a plurality of circuits to be selected, and a testing selector switch comprising the following instrumentalities: a contact bank containing a plurality of rows of terminals connected to said circuits, an associated set of test terminals, comprising one test terminal for each 15 row, a spindle with a pair of test wipers and a pair of connecting wipers, one of said test wipers adapted to co-operate with the row test contacts and another with the individual test contacts in each row, means for imparting motion to the spindle so as to move the row test wiper over the row contacts, means for imparting motion to the spindle so as to move the individual test wiper over the individual test contacts in any selected 20 row, and a shifting device responsive to the row test, and adapted when energized to deprive the first motor-means of energy, shifting the same to the second motor-means, whereby identification and connection 25 through the connecting wipers of a particular circuit is attained automatically by first segregating the row and then the individual location in the row.
11. In a telephone exchange system, line 30 circuits, line relays therefor, a primary selector switch containing connective terminals in rows connected to the line circuits, individual test contacts corresponding to the connective contacts in each row, row test contacts, one associated with each row, a 35 spindle carrying wipers adapted to co-operate with the connective terminals, the individual test contacts and the row test contacts respectively, and circuit connections from the line relays to the individual and row test contacts, whereby the switch may test and find a calling line by testing the row contacts to identify the row and the individual contacts in the row to identify 40 the line.
12. In a telephone exchange system, line 45 circuits, line relays therefor, a primary selector switch containing connective terminals in rows connected to the line circuits, individual test contacts corresponding to the connective contacts in each row, row test contacts, one associated with each row, a spindle carrying wipers adapted to co-operate with the connective terminals, the individual test contacts and the row test contacts respectively, and circuit connections from the line relays to the individual and row test contacts, whereby a call over any of the lines having terminals in the switch will start the same, and direct the switch to the calling line by successive testing of the row and individual contacts.
13. In a telephone exchange system, a plurality of line circuits, a selector switch containing terminals for said lines, actuating means for the switch responsive to current in the lines, a testing terminal for the switch and co-operating line testing terminals there-in with means operating over a portion only of the line test terminals to change their potential in response to calls over the corresponding lines, and means controlling the switch actuating means to direct the testing terminal of the switch to the individual test terminal of a calling line.
14. A telephone system including an operator's link circuit, an answering and a calling supervisory signal for said link circuit, a subscriber-controlled answering supervisory relay, a subscriber-controlled calling supervisory relay, circuits for said answering and calling supervisory signals controlled by said answering supervisory relay, and a second circuit for said calling supervisory signal controlled by said calling supervisory relay in response to a control exercised at the called substation.
15. A link circuit including a subscriber-controlled answering supervisory relay and a subscriber-controlled calling supervisory relay, a pair of supervisory signals for said link circuit, circuits for said signals controlled by said answering supervisory relay, and a second circuit for one of said supervisory signals controlled by said calling supervisory relay in response to a control exercised at the called substation.
16. A telephone system including a calling subscriber's line and a called subscriber's line, a link circuit for connecting said lines in conversational circuit, a calling supervisory signal for said link circuit, a relay controlled by the calling subscriber for closing an operating circuit for said supervisory signal, means for opening said circuit, and a relay controlled by the called subscriber for closing a second circuit for said supervisory signal.
17. In a telephone system, the combination with a calling subscriber's line, of a called subscriber's line, a link circuit for interconnecting the lines, a supervisory signal for said link circuit, means in said link circuit responsive to the joint control of apparatus on the calling and called subscribers' lines to display said signal, and means operative under the joint control of apparatus in the calling and called subscribers' lines for con-

tinuing the display of said signal independently of the apparatus on one of said subscribers' lines.

18. In a telephone system, the combination
5 with a calling subscriber's line, of a called subscriber's line, a link circuit for inter-connecting the lines, a supervisory signal for said link circuit, means in said link circuit responsive to the joint control of apparatus
10 on the calling and called subscribers' lines
- to display said signal, means operative under the joint control of apparatus in the calling and called subscribers' lines for continuing the display of said signal independently of the apparatus on one of said subscribers' 15 lines, and means responsive to disassociation of the said link circuit with one of said lines to retire the said signal.

In testimony whereof I affix my signature.
EDWARD E. CLEMENT.
